CLAIM

The ornamental design for a vehicle pit bar as shown and described.

DESCRIPTION

FIG. 1 is a top, front and left side perspective view of a vehicle pit bar showing my new design;

FIG. 2 is a front elevation view thereof;

FIG. 3 is a top plan view thereof;

FIG. 4 is a right side elevation view thereof;

FIG. 5 is a left side elevation view thereof;

FIG. 6 is a bottom plan view thereof; and,

FIG. 7 is a rear elevation view thereof.

In the drawings, broken lines depict portions of the vehicle pit bar that form no part of the claimed design.
